UNITED STATES PATENT OFFICE.

JOHN A. GROSHON, OF NEW YORK, N. Y., ASSIGNOR OF ONE-HALF TO
RICHARD M. MACDONOUGH, OF SAME PLACE.

STEAM-BOILER.

SPECIFICATION forming part of Letters Patent No. 427,074, dated May 6, 1890.

Application filed September 11, 1889. Serial No. 323,634. (No model.)

To all whom it may concern:

Be it known that I, JOHN A. GROSHON, a citizen of the United States, and a resident of New York, in the county of New York and State of New York, have invented certain new and useful Improvements in Steam-Boilers, of which the following is a specification.

The invention relates to improvements in boilers for generating steam, whether the latter is to be applied for power or heating purposes; and it consists in novel features of construction and arrangement hereinafter described and claimed, by which the water may be rapidly and effectually heated and steam generated without excessive pressure at any individual part of the apparatus.

The invention will be fully understood from the detailed description hereinafter presented, reference being had to the accompanying drawings, in which—

Figure 1 is a central vertical section of a boiler constructed in accordance with the invention, the section being taken on the dotted line X X of Fig. 2, which is a top view of the boiler, partly in section, on the dotted line Y Y of Fig. 1. Fig. 3 is a transverse section of the boiler on the dotted line Z Z of Fig. 1. Fig. 4 is an enlarged detached top view, and Fig. 5 a vertical sectional view, of one of a number of pipes through which the steam and heat respectively pass, and hereinafter specifically referred to.

In the drawings, A designates the exterior shell or casing, and B an interior shell or casing surrounding the parts which constitute the boiler, a space C being left between said casings for the purpose of forming an air-chamber to prevent any undue heating of objects which may be in proximity to the boiler.

The casing A is provided with apertures D, (shown by dotted lines in Fig. 1,) through which the air from the space C may circulate.

The casings A B are surmounted by a suitable cover E, and are supported upon the flange F, encircling the cast water-compartment G, which is in the outline of a circle, and is provided at its inner periphery with the annular flange H, upon which the grate-bars I are placed. Below the grate-bars I there is provided the circular ash-pit J; and be-

yond and inclosing said ash-pit is arranged the circular casing K, between which and the ash-pit is formed a space into which smoke and unconsumed gasses from the fire may pass and escape thence through the opening L into the smoke-pipe M. Upon the inner upper edges of the casing K is formed the flange N, which serves to support the water-compartment G at its outer edges, while at its inner edges said compartment is supported upon the upper edges of the ash-pit J, as illustrated in Fig. 1. The ash-pit J is in communication with the outlet-door O, and the heating-chamber of the furnace above the grate-bars I may be supplied with fuel through the door P. 65

Above the water-compartment G is provided a compartment of similar outline, (lettered Q,) which is in communication with the compartment G by means of tubes R, through which the water may pass from the lower to the upper compartment. Within the tubes R are secured flues S, which extend entirely through the water-compartments G Q, and are open at their lower and upper ends for the purpose of permitting the passage through them of the heat from the fire. Immediately above the door P is the short water-compartment T, which receives a few of the pipes passing downward from the compartment Q, it being impossible to extend said few pipes continuously from the water-compartment Q to the compartment G without interfering with the introduction of fuel upon the grate-bars I. The water-compartment T is connected at its ends with the water-compartment G by means of the larger tubes V, in order that the water from the compartment G may pass into the compartment T and thence upward through the tubes R to the compartment Q. The tubes R are arranged in the outline of a circle encompassing the grate-bars I, and form the walls of the heating-chamber, within which the fuel is placed.

In the drawings I illustrate two rows of the tubes R, connecting the water-compartments G Q; but it is obvious that as many rows or series of these tubes may be employed as may be desired, according to the capacity it is necessary that the boiler should have. At the inner edges of the circular water-com- 100

partment Q is secured, by means of bolts *a*, the circular steam-dome *b*, which is in communication with the compartment Q and is provided with the delivery-pipe *d*, through which the steam is permitted to pass to any desired point, either for use as power or for heating purposes. The water is fed to the compartment G through the pipe *e*, and this pipe is connected with the customary gage *f*, which is in communication through the pipe *g* with the water-compartment Q. Centrally within the upper part of the compartment is secured the reservoir *h* for fuel, said reservoir being provided with a suitable cover and being open at its lower end and operating, when in use, in the same manner as fuel reservoirs in base-burning stoves. The reservoir *h* need not be employed in the boiler unless desired; but its retention may be found convenient in instances where the boiler is employed for heating purposes—as for supplying steam to the registers of dwellings—since in such cases enough fuel may be fed in the morning to last during the day, whereas without the reservoir *h* it might be necessary to frequently add fuel through the door *P*.

In instances where the boiler is used for generating power an attendant would probably be necessary, and then the fuel-reservoir *h* could be conveniently dispensed with.

In the application of the tubes R and flues S to the water-compartment I preferably first introduce the ends of the tubes R to said compartments, and then expand them, as illustrated more clearly in Fig. 5, after which I insert the flues S and secure them by means of the screw-plugs *i*, in addition to expanding the flues immediately below said plugs, as also more clearly illustrated in Fig. 5.

In the employment of the invention the fuel is placed upon the grate-bars I and the fire started in the customary way, while the water is introduced through the pipe *e* into the compartment G, whence it passes upward through the series of tubes R into the compartment Q. The heat, it will be observed,

comes into contact with the outer surfaces of the tubes R, and also passes downward through the flues S, and thus acts upon the water a second time. The volume of water 50 in the tubes R is thus acted upon both at its outer side and at its inner side and over the most extended area that it seems possible to expose to the action of the heat. The heat and smoke, after ascending to the upper part 55 of the apparatus, pass downward through the flues S into the space between the ash-pit J and the surrounding casing K, and thence escapes through the smoke-pipe M. The steam generated passes into the dome *b*, and is then 60 delivered through the pipe *d*.

What I claim as my invention, and desire to secure by Letters Patent, is—

1. In a steam-boiler, the water-compartments G, Q, located, respectively, at the lower 65 and upper ends of the boiler, the series of vertical tubes R, connecting said compartments, and being separated from each other, so as to permit the circulation of heat entirely around them on its upward passage, 70 and the flues S, open at their ends and passing through said tubes, the latter inclosing the heating-chamber of the furnace, combined with the casing B, inclosing the tubes between said water-compartments, the inclosed ash-pit and the outer casing K, forming a space 75 beneath the compartment G, said space leading to the smoke-pipe, substantially as set forth.

2. In a steam-boiler, the water-compartments G, Q, and T, connecting-tubes R and V, steam-dome *b*, and flues S within the tubes R and open at their ends, combined with the inclosing-casing and the grate-bars within the line of the tubes R, substantially as set forth. 80 85

Signed at New York, in the county of New York and State of New York, this 9th day of September, A. D. 1889.

JOHN A. GROSHON.
